CLAIM

The ornamental design for a camera, as shown and described.

DESCRIPTION

FIG. 1 is a perspective view of a camera showing my new design; and

FIG. 2 is a front elevational view thereof.

FIG. 3 is a partially enlarged front, bottom, right perspective view thereof;

FIG. 4 is a partially enlarged front, bottom, left perspective view thereof; and,

FIG. 5 is a partially enlarged front, top, left perspective view thereof.

The broken lines depict portions of a camera in which the design is embodied that form no part of the claimed design. The dot-dash broken lines defining the boundaries of the claimed design form no part of the claimed design.

1 Claim, 5 Drawing Sheets
